*Calvin Bean, INVENTOR
BY Victor J. Evans*

ATTORNEY

UNITED STATES PATENT OFFICE

CALVIN BEAN, OF SYKESVILLE, PENNSYLVANIA

SHIRT

Application filed December 20, 1929. Serial No. 415,539.

This invention more particularly relates to certain new and useful improvements in the clothing art in the reinforcing of garments where the most wear occurs whereby the life 5 of the garment will be prolonged.

Another object of the invention embodies the provision and arrangement of panels for this purpose designed for attachment with the garment in such manner that its presence 10 will not detract from the general appearance of the garment.

An additional object of the invention consists in the formation of pockets between the garment proper and the panel by outlining 15 same by stitching whereby the outer surface of the panels will be free of the usual bulged effect by the formation of pockets thereon.

With the above and other objects in view, the invention further consists of the following novel features and details of construction, to be hereinafter more fully described, 20 illustrated in the accompanying drawings and pointed out in the appended claim.

In the drawings:—

25 Figure 1 is a fragmentary front elevation of a shirt of the split front type having the reinforcing panel arranged in sections upon opposite sides thereof.

Figure 2 is a horizontal sectional view 30 taken on line 2—2 of Figure 1.

Figure 3 is a view similar to Figure 1 of a shirt of the type which is split only from the collar to the waist and is put on by pulling same over the head.

35 Referring to the drawings in detail wherein like characters of reference denote corresponding parts, the reference characters 10 and 11 indicate the front sections of a split front type of shirt. In view of the fact that 40 the incorporation of the present invention with the shirt must be effected during the process of manufacture, it is necessary that the reinforcing panels 12 and 13 should overlap the side edges of the sections 10 and 11 45 and the adjacent side edges of the shirt back 14 in the manner suggested in Figure 2 of the drawings. The reinforcing panels 12 and 13 extend upwardly upon the front sections of the split front variety of shirt from points 50 below the waist or belt line and terminate in

a line across the breast of the shirt and in alignment with the arm pits. Both the upper and lower edges of the panels 12 and 13 are doubled and stitched upon the sections 10 and 11 and to those portions of the reinforcing seams at the junctures of association of the sleeves with the shirt proper. The flaps 15 and 16 receive the innermost edges of the associated sections and panels. Those portions of the reinforcing panels 12 and 13 55 upon the upper edges thereof are free of stitched engagement for appreciable distances to provide openings therebetween for pockets which may be created merely by outlining same through known processes of 60 stitching. Any number of vertical, horizontal, diagonal or curved lines of stitching may be arranged within the confines of the initially formed pockets to subdivide the latter into separate compartments for the 65 accommodation of pencils, scribing tools, measuring instruments and the like.

70 In order to form the separate compartments, that portion of the panel to be used may also be cut vertically, horizontally, diagonally or curved.

75 In Figure 3 of the drawings I have shown a modified form of shirt construction which is split only half way down the front and is put on or otherwise worn by pulling same over the head. The main characteristic or difference between the reinforcing of the shirt instant in contradistinction to the split front shirt previously mentioned resides in the fact that only one reinforcing panel, such 80 as indicated at 17, is employed. The panel is secured and the pockets formed thereon and between the adjacent surface of the shirt proper after the manner of the preferred form shown in Figures 1 and 2 of the 85 drawings.

90 As generally known to those familiar with the manufacture of shirts, the material used in the formation of seams has the same color effect as the shirt and the seams are therefore 95 unnoticed at a glance and for this reason the especially formed pockets in the types of shirts illustrated would not be noticed nor appreciated were it not for the provision and arrangement of a binding or wear strip 100.

18 upon either or both of the upper edges of the pockets and of differentiating color. This strip would not only distinguish or set off the entrance to the pocket but would also 5 serve as a means of attraction to prospective buyers.

Although I have shown, described and illustrated my improvement as being applied upon work shirts and the like to reinforce 10 same where the most wear occurs, it is obviously apparent that the principle may be also effectively employed in the manufacture of other forms of shirts requiring reinforcement peculiar to their use.

15 The invention is susceptible of various changes in its form, proportions and minor details of construction, and the right is herein reserved to make such changes as properly fall within the scope of the appended claim.

20 Having thus described the invention, what is claimed is:—

A front opening garment having an outer body comprising a reinforcing panel disposed entirely across the front and extending from 25 points below the waist upwardly adjacent the wearer's arm pits, said panel having portions thereof interposed between and secured to the seams for the front opening and side seams of the garment, said panel having portions 30 upon the upper edge thereof unstitched to the adjacent surface of the shirt body to provide entrances therebetween, and the shirt and panel being stitched together upon opposite sides and below the unstitched portions 35 spaced from the seams to define pockets in communication with the entrances and to obviate bulging between the shirt and panel.

In testimony whereof, I affix my signature.
CALVIN BEAN.
